YORK, A CORPORATION OF NEW YORK.

PNEUMATIC MECHANISM FOR CONVEYING ARTICLES.

1,413,743.

Specification of Letters Patent. Patented Apr. 25, 1922.

Original application filed October 1, 1920, Serial No. 414,034. Divided and this application filed April 4, 1921. Serial No. 458,483.

To all whom it may concern:

Be it known that we, EDWARD E. LAWRENCE and KENNETH D. Loose, citizens of the United States, and residents, respectively, of Jamaica and New York, in the counties, respectively, of Queens and New York, State of New York, have invented an Improvement in Pneumatic Mechanism for Conveying Articles, of which the following 10 description, in connection with the accompanying drawings, is a specification, like characters on the drawings representing like parts.

This application is a division of our co-pending application Serial No. 414,034, filed October 1, 1920.

This invention relates to pneumatic mechanism for conveying articles, the disclosed example of which is food products.

20 In order that the principle of the invention may be readily understood, we have disclosed a single embodiment thereof in the accompanying drawings, wherein—

Fig. 1 is a side elevation of the main parts 25 of a pneumatic conveying and stacking mechanism embodying the invention;

Fig. 2 is a front elevation of the structure shown in Fig. 1;

Fig. 3 is a vertical longitudinal section 30 taken upon the line 3—3 of Fig. 2; and

Fig. 4 is a vertical longitudinal section taken through the pneumatic drum or conveyor shown in Figs. 2 and 3.

We will disclose our invention with reference to the conveying and stacking of food products, without, however, limiting our invention thereto.

In a co-pending application, Serial No. 411,403, we have represented wholly mechanical means for conveying and for stacking articles, the represented type whereof is food products. The stacking mechanism proper represented in this case is substantially that shown and claimed in said companion application.

45 We are aware that heretofore it has been proposed to arrange or stack crackers for packing, but so far as we are aware, no satisfactory apparatus for this purpose has been placed upon the market, although numerous attempts have been made to provide apparatus for this purpose. The desirability of

satisfactory facing, conveying and stacking apparatus for articles of a disk like form and particularly for crackers and like food products is manifest, since the latter articles are now packed in small cartons or receptacles usually of the width and depth of a cracker and of a length sufficient to receive or accommodate a stack of substantial length. In satisfactorily stacking crackers or like food products, it is important that they all face the same way, that is, that they be face to back, and that the stacks or rows of the assembled crackers be accurately arranged and in face to back relation, so that a sufficient number to constitute a stack that will fill a single carton may be quickly taken by an operator or by suitable mechanism from a row in the conveying and stacking mechanism and be inserted with a minimum loss of time into the carton or receptacle.

The mechanism herein disclosed constitutes the preferred pneumatic embodiment 75 of the broad invention that is more generally and generically claimed in said companion application, and accomplishes the desirable results that we have above indicated.

80 Referring more particularly to the drawings, we have at 1, 3, 4, 5 and 6 indicated a framing preferably in the nature of an elongated table-like structure partly broken away in Fig. 1 and desirably adapted to support certain conveyor chains indicated at 7 in Fig. 1, and by which filled pans 8 of crackers 9 or other like food products, or if desired articles of any nature but desirably of a disk-like form, may be conveyed from any suitable source. At 10 in Figs. 1 and 3, we have represented the empty pans that have passed in operative relation to the mechanism of our invention and from which the crackers or the like have 95 been removed pneumatically. Desirably the empty pans are returned in any suitable manner and not herein disclosed to the place where they are to be re-filled. Within the scope of the invention the pans may be fed 100 either from the left or from the right viewing Fig. 1, toward the pneumatic mechanism herein disclosed. Viewing Fig. 3, it will be observed that the filled pans 8 are

conveyed by the chains 7 along channel irons 10' directly beneath a rotating drum 11 that extends across the entire width of the conveyor chains and pans thereon, is provided 5 throughout its surface with a very large number of small, closely positioned perforations 12 and is at one end connected with a conduit 13 that is itself in communication with a blower or suction device of any approved type, but preferably one by which a strong suction may be created sufficient to lift the crackers or other articles from the filled pans 8 and to cause them to cling to the rotating surface of the drum 11 until 10 released therefrom as hereinafter set forth. It has been found in practice to be very desirable to agitate the crackers upon the pan 8 when beneath the drum 11. It has been found that such agitation very slightly 15 separates or elevates the crackers from the pan 8 or at least permits a slight film or layer of air to enter beneath the crackers, with the result that such agitated crackers are more readily responsive to the suction 20 created at the surface of the drum 11. While for this purpose any suitable means may be provided, we have herein represented the following means.

Upon a shaft 14 suitably supported in the 25 framing are two cams 15 herein represented as pentagonal in shape. In the rotation of the said cams the points 16 and the flat faces 17 alternately are brought into contact with the under face of a vertically movable 30 frame 18 upon which the channel irons 10' rest beneath the drum 11 with the result that at such point the channel irons, conveyor chains and the filled pans are sharply agitated so as to render the contents of said 35 pans more susceptible to the suction existing at the surface of the drum 11. Desirably the agitation is in such a direction as slightly to lift the crackers or other articles, but within the scope of the invention agitation 40 in any suitable direction may be resorted to for the purpose stated, as for example, in a transverse direction.

The frame 18 is supported by a suitable 45 number of upright rods or posts 19, preferably four, which at their lower ends pass through openings in parts 20 of the frame and therebeneath are surrounded by strong coiled springs 21 that are compressed between said part of the framing and nuts and 50 washers 22 upon the lower ends of said posts or rods, the construction and arrangement being such that the frame 18 is intermittently and rapidly vibrated against the action of the coiled springs 21, the latter 55 serving to return the frame 18 to its lower or normal position.

The shaft 14 may be rotated in any suitable manner. For the purpose we have represented it as provided with a sprocket 23 60 about which passes a sprocket chain 24, also

passing about sprockets 25, 26 upon shafts 27, 28 suitably supported in the framing. The sprocket chain 24 is endless and is driven in any suitable manner not herein necessary fully to disclose, but if desired 70 from a variable speed device indicated generally at 29 in Fig. 1, and desirably driven as by a belt from an electric motor, not herein shown. The construction and relation of parts are such that through the said 75 variable speed device any desired rate of speed may be imparted to the sprocket 51 and hence to the sprocket chain 50 and the parts driven thereby.

The shaft 14 is mounted in vertical, adjustable bearings, and to that end the sprocket chain 24 is so constructed and arranged as to permit of such adjustment of the shaft. In order to adjust the shaft 14 in a vertical direction, we have herein chosen 85 to provide a shaft 30 adapted to be turned by a hand wheel 30'. Upon said shaft 30, at the opposite ends, we provide fibre cams or eccentrics 31, upon each of which rests a member 32 constituting a lower prolongation of a bearing 32' for said shaft. Said members 32 may be supported wholly upon said cams or eccentrics 31 or, if desired, we may provide said members with vertical slots to receive bolts tapped into the framing and carrying nuts to be slackened when it is desired to adjust the shaft 14 by the cams or eccentrics 31. The shaft 14 is adapted to be held in the desired position of 90 rotative adjustment by ratchet and pawl 32''. 100

We provide for vertically adjusting the shaft 14 in order to permit the pans to be shaken harder or more gently as desired and also to permit the said pans to be brought closer to or kept from the drum 11 according as the biscuits, crackers or other articles thereon are thin or thick.

The drum 11 may be of any suitable length, but it is desirably several feet in length, and it has required very extensive 110 experimentation so to construct the drum and the parts immediately co-acting therewith as to insure a substantially even suction action at the surface of the drum throughout the entire length thereof. Normally the suction is greatest at that end of the drum that is connected as at the conduit 13, Figs. 2 and 5, with the fan or blower. It is of great importance and particularly 115 where the crackers or other articles are to be delivered from the drum in a comparatively large number of rows, each consisting of articles arranged edgewise, that there be a substantially uniform suction action throughout the length of the drum so that 120 the crackers or other articles may be delivered into the several rows at a rate approaching uniformity. After much experimentation, we have provided the following 125 mechanism interiorly supported with re- 130

spect to the drum 11 and also constituting means whereby the suction is cut off at successive portions of the surface of the drum when said successive portions reach a position where the crackers are to be dropped or otherwise discharged into the several rows above referred to.

A shaft or cross member 33 is stationarily mounted in any suitable manner and as for example at one end in a suitable upright 34 extending to the floor 35, and at the other end as shown in Fig. 4 in a hub 36 of a spider 37, the ring or annular member 38 whereof is supported upon the conduit 13 extending as stated from the framing 39 of the blower. The shaft 33 is preferably hollow to permit oiling of various parts of the mechanism. The drum 11 is itself mounted to rotate upon or about the stationary shaft 33 and for that purpose it is provided with an outer closed end 40 having a hub 41 through which the stationary shaft 33 passes. The hub 41 is supported upon a suitable part 42 of the framing and at its outer end is provided with a gear wheel 43 meshing with and driven by a pinion 44 upon a shaft 45, having fast thereon a gear wheel 46, itself meshing with and driven by a pinion 47 upon a shaft 48 having fast therewith a sprocket 49 about which passes a sprocket chain 50 driven by sprocket pinion 51 upon the shaft 52 of the variable speed device 29.

At its opposite or left hand end viewing Fig. 4, the drum 11 is provided with a ring 53 desirably beveled as indicated and rotating against the inner correspondingly beveled face of the stationary ring 38.

The construction and arrangement are such that the drum 11 is rotated at a suitable speed and conveys the crackers or other articles from a filled pan directly beneath the same and in contraclockwise direction viewing Fig. 3, to the upper ends of chutes or receivers not shown.

Fast upon the stationary shaft 33 are a suitable number of spider-like members 54, three of which are represented in Fig. 4.

Desirably these said members are of a somewhat segmental form and are represented in Fig. 3 as having three radiating arms 55, extending from hubs 56 to segments 57 here shown as extending through substantially 180 degrees. Upon the said segments 57 is supported a stationary baffle drum 58 which is substantially of the length of the drum 11 and throughout about 180 degrees of its own surface is in contact with the inner surface of the drum 11 as clearly indicated in Fig. 3. The said baffle drum 58 is at one part provided with a substantially radial portion 59 of the full length of said baffle drum and extending inwardly at certain of the radial arms 55 a sufficient distance where it merges into a spiral surface 60 which, as represented in Fig. 3, gradually approaches

the inner surface of the drum 11 and finally merges into the surface 58 at the full diameter of the said baffle drum.

Because of the described construction there is more static pressure or suction at or in the vicinity of the radial portion 59 than at the succeeding parts, such static pressure or suction gradually decreasing as the point is approached where the surface 60 merges with the surface 58.

The surface of the said baffle drum composed of the surfaces 58, 59, 60 is imperforate excepting for the provision of a certain number of openings, two of which are indicated at 61, 62 in Fig. 4.

Desirably and in that type of the invention herein shown there are provided four of the openings 61, 62, and between adjacent openings spiral or semi-crescent shaped partitions 63 are provided integral with or rigid with the surfaces 59, 60, and filling at intervals the entire space between the spiral surface 60 and the inner face of the drum 11, it being understood that the said partitions are relatively thin and occupy comparatively little space lengthwise of the drum 11. The said partitions are provided merely to cut off communication between the several openings 61, 62, etc. between the spiral surface 60 and the inner surface of the drum 11.

Desirably each of the openings 61, 62, etc. is provided with a sliding damper or member 64 mounted in guides 65, 66 so that the relative areas of the several openings 61, 62, etc. may be such as are found best suited to secure uniform suction at the outer surface of the drum 11 from end to end thereof. We have found after a great deal of experimentation that the several openings 61, 62, etc. should be of different sizes according to their distance from the conduit 13. For this purpose we have provided adjustable means, herein typified by the dampers 64, whereby the areas of the said openings may be relatively proportioned to obtain the desired result, namely, substantial uniformity in the suction at the surface of the drum 11 throughout the entire length thereof.

Viewing Figs. 3 and 4, it will be evident that the air is drawn through the openings 12 of the drum 11 and through the several openings 61, 62, etc., and that as a consequence the crackers or other articles 9 will be drawn forcibly against the rotating surface of the drum 11 immediately to the right viewing Fig. 3 of the radial portion 59 of the baffle drum and will be held thereagainst in the rotation of the drum 11 until the inner surface of the latter meets the surface 58 of the baffle drum, that is, along a longitudinal line of meeting of the surfaces 60, 58. At and contraclockwise beyond said meeting line the suction is cut off from the surface of the drum 11, and therefore the crackers or other articles are released so that

130

they may be discharged in any suitable manner and preferably to permit them to be stacked.

Obviously, however, the crackers or other articles may be handled in any desired manner when discharged from the drum 11.

While our invention has been described with reference to food products, it is clearly to be understood that it is in no wise limited 10 to such use but is of broad application.

Having thus described one illustrative embodiment of the invention, we desire it to be understood that although specific terms are employed, they are used in a generic 15 and descriptive sense and not for purposes of limitation, the scope of the invention being set forth in the following claims.

Claims—

1. Mechanism for conveying disk-like 20 articles comprising a movable member having a perforated surface at which suction is adapted to be created, means to present a series of disk-like articles to said surface, and means to move said surface to convey 25 the articles to the desired place.

2. Mechanism for conveying disk-like 30 articles comprising a rotatable member having a perforated surface at which suction is adapted to be created, means to present a series of disk-like articles to the surface of said rotatable member, and means to rotate 35 said member to convey the articles to the desired place.

3. Mechanism for conveying disk-like 45 articles comprising a rotatable member having a perforated surface at which suction is adapted to be created, means to present a series of disk like articles to said surface, a baffle within said member to cut off suction 50 at predetermined parts of the surface so as to release the articles, and means to move said member.

4. Mechanism for conveying disk-like 45 articles comprising a rotatable member having a perforated surface at which suction is adapted to be created, means to present a series of disk like articles to said surface, a stationary baffle positioned within said 50 rotatable member, and means to rotate said member about the baffle so that successive portions of the surface of said member receive the articles by adhesion and subsequently release the same.

5. Mechanism for conveying disk-like 55 articles comprising a rotatable member having a perforated surface at which suction is adapted to be created, and a baffle mounted within the rotatable member and having a surface gradually approaching the inner 60 surface of the rotatable member.

6. Mechanism for conveying disk-like 65 articles comprising a rotatable drum having a perforated surface at which suction is

adapted to be created, and an interior baffle of general drum-like form having a surface, 65 a portion of which is concentric with that of the rotatable member and a portion of which is of a spiral form.

7. Mechanism for conveying disk-like 70 articles comprising a rotatable drum having a perforated surface at which suction is adapted to be created, and an interior baffle having a surface composed of concentric, spiral and radial parts connected together and cooperating to permit articles 75 to adhere to the surface of the drum and subsequently to be released therefrom.

8. Mechanism for conveying disk-like 80 articles comprising a suction drum having a perforated surface, and an interior baffle 85 having means to distribute the suction with substantial uniformity throughout the extent of the drum and means to present a series of disk like articles to the perforated surface of said drum.

9. Mechanism for conveying disk-like 90 articles comprising a suction drum having a perforated surface, and a baffle within said drum having a series of openings ranging longitudinally of said baffle, and partitions 95 between said baffle openings and extending substantially to the inner surface of the drum.

10. Mechanism for conveying disk-like 95 articles comprising a suction drum having a perforated surface, means to rotate said drum, and a baffle within said drum, said baffle having a surface that is partly concentric with that of the drum and partly spiral with relation thereto, said spiral portion of the baffle having a series of openings 100 therein.

11. Mechanism for conveying disk-like 105 articles comprising a suction drum having a perforated surface, means to rotate said drum, and a baffle within said drum, said baffle having a surface that is partly concentric and partly eccentric with relation to the inner surface of the drum, and a series of partitions between the eccentric and concentric portions of said baffle and drum, there 110 being openings in the baffle between said partitions.

12. Mechanism for conveying disk-like 115 articles comprising a perforated suction drum, means to rotate the same, a stationary baffle within the drum having openings along the length thereof through which suction may be created at the surface of the drum, and means to vary the size of said openings 120 in the baffle.

13. Mechanism for conveying disk-like 125 articles comprising a movable member having a perforated surface at which suction is adapted to be created, a support for the articles to be acted upon by said movable mem-

ber, and means to agitate the articles upon said support to facilitate the adhesion of said articles to the surface of said member.

14. Mechanism for conveying disk-like articles comprising a rotatable suction drum having a perforated surface, a conveyor for the articles to be acted upon by said drum, and means to agitate said articles between

said support in proximity to the surface of the drum thereby to facilitate the adhesion 10 of the articles to the surface of the drum.

In testimony whereof, we have signed our names to this specification.

EDWARD E. LAWRENCE.
KENNETH D. LOOSE.
